Application October 26, 1932, Serial No. 639,638
In Great Britain November 3, 1931

17 Claims. (Cl. 66—86)

This invention relates to the production of textile fabrics, and more particularly to the production of knitted fabrics on warp knitting machines.

5 The object of the invention is to improve warp knitting machines with the object of greatly increasing their rate of working and smoothness of operation, and rendering them capable of knitting fabrics of better and more uniform 10 quality.

It has now been found that a much improved rate of operation can be effected by balancing various parts of the machine which are required to perform rapid, non-rotary motions. According 15 to the invention, therefore, there are provided in connection with such parts balance members which are given movements of like angular velocity and magnitude in the opposite sense to those of the parts balanced, so as to 20 give rise to equal and opposite resultant forces and neutralize the effect of the forces employed to produce the knitting movements. The balancing masses are suitably distributed throughout the machine in correspondence with the distribution 25 in the machine of the masses to be balanced.

In machines of the type with which the present invention is concerned the knitting elements, e. g. the needles, the sinkers and the presser 30 bars, are mounted and operated in the form of bars extending the whole length of the machine and are actuated by cams usually disposed on a common cam shaft. Conveniently each bar is supported at a number of points along its length 35 and is driven at some or all of such points by means of the cam and such cam shaft. The cams themselves are preferably so designed as to be in balance on the cam shaft, so that they exert a flywheel effect which is of assistance in 40 procuring smooth running.

The needle, sinker, and presser bars being actuated at several points along their length, they can be regarded as the equivalent of a number of masses concentrated at these points. That 45 is to say, the oscillating masses which are distributed substantially uniformly along the length of the machine could be replaced by a plurality of masses of the same total amount arranged at the several operating points along the machine, in fact, the forces tending to set up vibration are applied at these points and are proportional to the mass there supported.

The invention therefore comprises the provision 50 of balancing masses similarly distributed along the length of the machine, and preferably

in number equal to the number of operating points employed for each oscillating member. Each balancing mass oscillates about the same axis as the mass that it balances, being arranged at the same effective radius and given a movement precisely similar in velocity but in the opposite direction, so as to produce neutralization of the vibrational forces obtaining.

It is convenient to carry the balancing masses on rocker arms which are similar in construction and material to those operating the knitting members, so that the addition to the rocker arms of masses equivalent to the knitting members provides the necessary balance. Of course, if the knitting members have intermediate supporting rocker arms, as is convenient in the case of the needle and presser bars, the mass of these arms must be taken into account in computing the mass of the balance weights.

One balance weight could only be effective if 75 placed at the same radius from the centre of oscillation as that of the mass to be balanced, but this arrangement is precluded because this mass runs continuously along the length of the machine. At least two balancing masses are, therefore, required in each of the balancing members; 80 these masses are placed at radial distances from their centre of oscillation which enable the masses to be accommodated conveniently with respect to the mass that they balance. It has 85 been found that in general two balance weights can be employed in connection with each operating point.

The moments of inertia of the two weights must together equal the moment of inertia of 90 the mass to be balanced about the axis of oscillation. Further, the sum of their mass moments about this axis or radii which are the projections of their two radii on the plane passing through the centre of gravity of the mass to 95 be balanced and the axis must be equal to the mass moment of the mass itself about the axis.

By placing one balancing lever alongside the lever of the system it is required to balance, the resultant forces do not quite neutralize each 100 other, but this arrangement is satisfactory in practice, since the forces constitute a couple which is extremely small in magnitude and not sufficient to set up more than the very slightest vibration.

The two balance weights may, as stated above, be placed at any convenient radial distance from the rocker shaft. Where convenient, one may be placed at a greater radial distance than that of the mass to be balanced and the other at a less 110

distance. If, however, the construction of the machine does not permit such an arrangement, other positions for the weights may be adopted, the masses of the weights being adjusted in accordance with their radii so as to fulfill the requirements of the two equations given above with regard to the moments of inertia and the mass moments.

Balancing of the guide bar mechanism is carried out in a manner similar to that described above. Since, however, the mass of the guide bars and their rocker and supporting arms lies in a position in or close to the path of the rear set of warp threads, it is impossible to provide a balancing mass as the disposition would interfere with the passage of warps to the needles. This difficulty may be overcome by the provision of a weight moving with the guide bar mechanism so as to shift the mass of the guide bars and their rocker and supporting arms away from the path of the rear set of warp threads. By suitably positioning this weight the mass of the guide bars and associated parts may be brought to such a position that their motions may be balanced by means of a single balance weight instead of by two balance weights.

The rocker shafts of the machine are, as previously stated, made sufficiently strong to resist the torsional forces involved in applying the oscillatory movements, and at the same time they are strong enough to resist the small couples arising from equal and opposite balancing forces.

As described above the actuating and balance cams can all be arranged on a single cam shaft, and even if the operating cams themselves are not in balance, the provision of the balance cams enables complete balance of the cam shaft to be easily obtained. Therefore, the whole of the elements involved in high speed oscillatory movement are so arranged as to produce the very minimum of vibrational forces. Conveniently the operating and balance cams are constructed as a single element so that the timing of the balancing member is always correct with respect to the timing of the corresponding knitting member. Thus the two cam elements may be mounted on a common hub, which arrangement facilitates the formation of the cams themselves while allowing them to be placed close together so as to reduce to a minimum the small couple resulting from the equal and opposite forces applied at the two cams.

The warp feed mechanism may be of any suitable type but is preferably a kind specially adapted for a warp knitting machine working at a high speed. Any suitable type of fabric take-up mechanism may be employed, this being conveniently driven by ratchet gear from the cam shaft of the machine.

It is preferred to make the machine frame of extremely rigid construction so that it does not depend upon secure anchoring in position to resist vibration.

The invention will now be described in greater detail with reference to the accompanying drawings but it is to be understood that this description is given by way of example only, and is in no respect limitative.

Figure 1 shows a sectional side elevation of a warp knitting machine according to the invention, showing the knitting parts and the rocker arm and cam drive for the needle bar;

Figure 2 is a view of the balancing mechanism for the needles and associated parts;

Figures 3 and 4 show respectively the sinker

bar operating mechanism and the balancing mechanism for the sinker bar and associated parts;

Figures 5 and 6 show respectively the presser bar operating mechanism of the balancing mechanism for the presser bar and associated parts; and,

Figure 7 is a rear view of one-half of the machine, showing the assembly of the operating and balancing mechanisms along the length of the machine, together with details of the mechanisms which are described more fully in U. S. applications S. Nos. 639,631, 639,632, 639,633, 639,634, all filed Oct. 26, 1932, corresponding to British applications Nos. 21763/32, 21764/32, 21765/32 and 21769/32 dated 3rd November, 1931.

Referring to Figure 1, the machine comprises a frame 10 at the top of which is carried a bracket 11 supporting two warp beams 12, 13. Warp threads 14, 15 are drawn from the beams 12, 13, and pass over tension bars 16, 17 pivoted on the bracket 11. The warp threads 14, 15 proceed from the bars 16, 17 to thread guides 19, 20 which conduct them to the needles 21 where they are knitted into fabric by the interaction of the two rows of guides 19, 20, the needles 21, sinkers 22, and presser bar 23, the fabric 25 proceeding from the needles 21 to a take-up device 26. For the sake of clearness the levers carrying the guides 19, 20, the sinkers 22 and the presser 23 are not illustrated in this figure, but it may be here stated that the guides 19, 20 swing about the shaft 28, the sinkers 22 about the shaft 29, and the presser 23 about the shaft 30.

Needle operation

The needles 21 are held in a needle bar 31 which is moved up and down by means of a plurality of levers secured to a shaft 33 so as to swing in unison. The butt end 34 of the lever 32 carries two cam bowls 35, 36, and these cam bowls work on opposite sides of a cam 37 mounted on a disc or hub 38 rotating on a cam shaft 39. The cam 37 operates upon the butt end 34 of the lever 32 and gives to the needles 21 the motion requisite for knitting. It will be seen that the needles 21 and the needle bar 31, together with its intermediate, non-driven supporting arms to be referred to later, since they extend along the entire length of the machine, form a very considerable mass which is oscillated up and down once in each course of knitting. The needle bar 31, together with its needles 21 and intermediate supporting arms to be referred to later, can however, be regarded as a plurality of masses which are all caused to move up and down by the forces applied by the rocker arms 32. The tendency to vibration resulting from these moving masses and the forces producing their motion is balanced by the provision of moving balance weights of equivalent mass and requiring equal and opposite forces to bring about their motion.

The oscillatory movement of the needles 21 and needle bar 31 are balanced by means of weights shown separately in Figure 2 in their correct relationship to the shafts 29, 30, 33 and 39. Two weights 41, 42 are provided whose masses and distances from the rocker shaft 33 are appropriate to the mass to be balanced and its distance from the same shaft. Thus regarding the mass of the needles and needle bar concentrated at any particular rocker lever 32 to be M, and the distance of its centre of gravity 150

from the axis of the shaft 33 to be r , and the masses of the balance weights 41, 42 and the distances of their centres of gravity from the axis to be M_2 , M_3 and r_2 , r_3 respectively, suitable values can be given to these latter quantities which will enable them to neutralize substantially all vibration arising from the operation of the needle bar.

It will be seen from the drawings that the space available for balance weights is exceedingly limited, not only because of the number of mechanisms to be operated in the length of the machine (as will appear more clearly later), but also because of the concentration of the guides, sinks, and presser, and their bars and operating mechanisms in a space close to the needles. The positions to be occupied by the balance weights have, therefore, to be chosen carefully with regard to the positions occupied by the various knitting elements and their operating mechanisms, and also depend on the form of balance lever which can be accommodated.

Reference to Figure 2 shows the balance lever 43 arched to span the cam-shaft 39 with sufficient clearance for its own motion, and the weights 41, 42 situated one between the rocker shaft 33 and the sinks and presser, and the other between the cam shaft 39 and the rocker shaft 29. That is to say, the values of r_2 and r_3 are closely limited. Greater latitude is, however, possible with regard to the magnitude of the balancing masses, since these can be extended lengthwise of the machine and so can be made relatively great notwithstanding the smallness of their cross-sectional area as imposed by the space restriction above referred to. M_1 , r_1 (the mass and effective radius of the needle bar) and r_2 , r_3 can thus be regarded as constants and values of M_2 , M_3 which will give practically complete balancing can be determined by the two following equations:—

$$M_1r_1 = M_2r_2^2 + M_3r_3^2$$

$$M_1r_1 = M_2a + M_3b$$

where a and b are the radial distances of the centres of gravity of the masses M_2 , M_3 projected on to the plane passing through the centre of gravity of the mass M_1 and the axis of the shaft 33. These equations assume that the curvature of the path of the needles can be ignored in view of the relatively small length of path traversed.

For any particular cross-section ascribed to either of the two balance weights, a length can be chosen for the weight to give it the required mass. In Figure 2, therefore, the actual cross-sections of the weights 41, 42 must not be taken as necessarily being proportional to their masses, since either weight can extend for a suitable distance lengthwise of the machine to bring its mass to the magnitude necessary to satisfy the balancing equations given above. Of course, the balance lever 43 itself adds to the balancing mass and must be taken into account in determining their magnitude. It will be seen that the operating lever 32 is also arched over the shaft 39 in extending to its butt-end, occupying practically the whole of the space between the shafts 33, 39. The construction of the operating and balance levers will be set out more fully hereafter.

The butt end 44 of the balance lever 43 is provided with cam bowls 45, 46, which are operated upon by a cam 47 shown in dotted lines, being on the opposite side of the cam plate 38

to the cam 37 shown in Figure 1. The cam operating the weights 41, 42 is of such profile as to give to the weights 41, 42 a motion opposite in direction but equal in velocity to that given to the needle bar 31 by the cam 37, so that the oscillating forces developed by the needle bar 31 and the weights 41, 42 are equal and opposite and so balance one another. Actually, since the balancing forces must necessarily act in a different plane from the forces they neutralize, a couple must ultimately result from using one balance lever 43 in connection with each operating lever 32, but by placing the levers side by side, as shown in Figure 7, the magnitude of such couples can be made of negligible value.

Sinker operation

In Figure 3 one of a number of rocker levers 50 carrying the sinker bar 51 is shown, the bar 51 extending the whole length of the machine and having the sinks 22 mounted thereon in a long series. Similarly to the needle rocker lever 32 shown in Figures 1 and 2, the rocker lever 50 is provided at its butt end 52 with cam bowl 53, acting one on each side of a cam 54 projecting from the face of a disc 55 mounted upon the cam shaft 39. The sinks 22 are shown in their forward position and the limits of motion of the butt 52 of the lever 50 are indicated in dotted lines.

The mass of the sinker bar 51 and the sinks 22 along the length of the machine is balanced by means of weights 57, 58 carried and actuated by a lever 59 as shown in Figure 4. Here again the butt end 60 of the lever 59 is provided with cam bowls 61, the cam bowls being operated upon by a cam 62 shown in dotted lines, which lies on the opposite side of the cam disc 55 to the cam 54. Since the sinker bar 51 is in its forward position the balance weights 57, 58 are shown in Figure 4 in their corresponding rearward position, the forward limit of motion being shown in Figure 4 in dotted lines. In

the three pairs of Figures 1—2, 3—4 and 5—6, the operating and balance levers respectively are shown in substantially correct position relative to each other. For example in Figure 1, the needle lever 32 is at the end of its counter clockwise movement and balance lever 43 at the end of clockwise movement. As in the case of the needle balance mechanism, the positions and cross-sections of the balance weights 57, 58 are closely determined by the space available. The weight 57 lies between the cam-shaft 39 and the sinker rocker shaft 29, while the weight 58 is accommodated between the shaft 29 and the fabric proceeding to the take-up device. The masses necessary for balance are determined from the magnitude and effective radius of the mass of the sinker bar regarded as concentrated at each operating lever 50 and the radii chosen for the weights 57, 58 as in the case of the needle balance weights 41, 42, the weights 57, 58 being extended for a suitable length in accordance with their cross-sections.

The operating and balance levers 50, 59 extend to their butts between the cam-shaft and the pressure rocker shaft, the particular form of the levers being referred to again hereafter. The sinker operating and balance levers are arranged closely side by side to minimize the magnitude of the couple resulting from the forces involved.

Presser operation

The presser 23 is mounted on a bar 66 car- 150

ried on the ends of a number of long swan-necked levers 67 swinging about the shaft 30. The lever 67 passes between the shaft 33 and the sinker bar 51, and then downwardly between the shafts 39, 29 to the shaft 30. It also extends sidewardly immediately below the shaft 39 to form a butt end 68 of the lever 67 carrying two cam bowls 69 which are operated upon by the two faces of a cam 71 carried on a cam disc 72 mounted on the cam shaft 39. The lever 67 is shown in its rearward position, the forward limit of motion being indicated in dotted lines.

In Figure 6 presser balance weights 73, 74 are shown carried on a lever 75, whose butt end 76 is provided with cam bowls 77.

The weights 73, 74 are carried one between the butt end of the lever 75 and the other on a forward extension of the lever below the fabric passing to the take-up device. The positions and dimensions of the balance weights are determined from the magnitude and effective radius of the mass of the presser bar concentrated at each operating lever as in the case of the needle and sinker balance weights. The operating and balance levers are arranged closely side by side to minimize the resultant couple. The cam bowls 77 are operated upon by a cam 79 shown in dotted lines on the face of the cam disc 72 opposite the cam 71. Here again the presser bar 66 being in its rearmost position, the balance weights are in their forward position, their other limit of motion being shown in dotted lines.

35 *Operating lever and balance lever construction*

Though the moving masses represented by the operating and balance levers may be relatively small with respect to the moving mass of the needle bar, it is preferred to make the levers of light but strong material, such as aluminum alloy or steel with a high modulus of elasticity so as to reduce their inertia, and consequently the power required to drive them, to a minimum, while giving the greatest resistance to deflection under the forces to which they are subjected. The sections of the levers are preferably in the general form of a U or H so as to resist bending, the webs of the sections being cut away for the sake of lightness as shown in Figures 1 to 6. Further, the section is made as great as possible to secure rigidity, especially at the parts subjected to the greatest bending movements. The several forms of lever illustrated show how these large sections can be obtained. The weights are conveniently formed on the balance levers by filling suitably dimensioned cavities with heavy metal such as lead. Preferably, the cross-sections of the weights are of symmetrical form, or at any rate of simple geometrical form, for the accurate determination of their centres of gravity and the computation of the amount of loading material required to fulfil the balancing equations.

The butt-ends of each pair of operating and balancing levers are so disposed that their cam bowls act at the same angular positions on their two cams. The cam bowls are preferably adjustable in order to regulate the field of traverse of the parts operated and/or to take up wear. In the drawings, each cam is shown arranged to give one complete oscillation for each revolution, though, of course, more than one oscillation could be effected if desired. The large periphery of the cams assists in the smooth operation of the mechanism and enables the

movements to be effected without unduly high acceleration of the parts, even at very high speeds of operation, a feature which is of direct advantage in reducing the magnitude of the forces involved.

General arrangement

Figure 7 shows an assembled view of the back of one-half of the machine provided with balanced knitting parts described above. In this figure three frame sections 10 are shown, and the shafts 28, 33, 39, 30 are clearly visible along the whole length of the machine, the shaft 29 being concealed behind the shaft 39. In addition, one set of guides 20 is shown broken towards the right hand end of the machine, a set of needles 21, a sinker bar 51, and presser bar 66 carrying the presser 23 towards the left hand end of the machine. Operating rocker levers 32 for the needle bar 31 are shown at three points on this figure together with the cam discs 38 with the cams 37 on the right hand side thereof, operating on the cam bowls 35 mounted on the levers 32. The lever 43 balancing the movement of the needle bar is shown in each case on the left hand side of its corresponding needle-bar operating lever 32. It will be understood that cam bowls 36, 46 utilized for operating the needle bar and the needle balance weights respectively lie inside the cams 37, 47 and are therefore not visible.

The lever 32 on the left hand side of the figure is suitably broken away to show the I-section form of the lever as at 160 and the connection of the lever 32 to the needle bar 31. Near the right hand end of the machine, a non-operated intermediate needle rocker arm 163 is shown, this arm merely serving to support the needle bar 31 and not to operate it. As has already been indicated, the mass of this lever is taken into account in computing the value of the masses to be balanced. Like the operated levers, it is therefore made of light but rigid construction.

The sinker operating levers 50 are also clearly shown at two points, and it will be understood that these levers 50 are mounted upon the shaft 29 which lies behind the shaft 39. Part of the shaft 33 is broken away to show the upper end of the lever 50 together with part of the sinker bar 51 in the left hand half of the machine. The rocker arm 50 is operated by cam bowls 53 one of which being inside the cam 54 is shown in dotted lines. On the other side of the cam disc 55 to the cam 54 is the balance cam 62 engaging with cam bowls 61 of the balance lever 59. The balance weight 57 attached to the balance lever 59 is shown about the shaft 39.

The presser rocker arms 67 are shown at two points of view in the right hand side of the machine being in full. In addition three intermediate levers 170 are shown for the presser arm, these levers merely supporting the presser bar and being keyed to the lever 30 without being actuated. The rocker arms 67 are provided with cam bowls shown at 69 operating on cams 71 carried by the cam disc 72. On the other side of each cam disc 72 is a balance cam 79 operating upon cam bowls 77 carried by the presser balance lever 75.

The operating and balance levers of each of the several bars are arranged as uniformly as possible along the length of each bar, subject to the provision of sufficient space and the necessity for dividing the machine by the inter-

mediate frames 10. Of course, where uniform spacing of the levers is not possible, the balance weights are adjusted in size in accordance with the lengths of bar supported at each rocking lever and with the masses of any intermediate supporting levers, as in the case of the needle and presser bars.

The needle, sinker and presser bars are all of rigid construction so as to resist deflection by bending between points of support. Further, in order to reduce the oscillating masses to a minimum, a light construction of needles and sinkers should be adopted. In this connection, reference may be had to U. S. application S. No. 639,637 filed Oct. 26, 1932 corresponding to British application No. 21768/32 dated 3rd November, 1931.

What we claim and desire to secure by Letters Patent is:—

1. A warp knitting machine comprising knitting elements, balancing elements auxiliary thereto, means for actuating said knitting elements, and means for actuating said auxiliary elements in synchronism with but in the opposite sense to said knitting elements, the mass of the auxiliary elements in relation to the mass of the corresponding knitting elements being such that the auxiliary elements and the knitting elements require substantially equal driving forces, and the driving means for the auxiliary elements being so disposed with relation to those of the knitting elements that the driving forces substantially oppose each other so that vibrational forces resulting from the driving of the knitting elements are substantially neutralized.

2. A warp knitting machine comprising a needle bar, balancing elements auxiliary thereto, means for actuating said needle bar, and means for actuating said auxiliary elements in synchronism with but in the opposite sense to said needle bar, the mass of the auxiliary elements in relation to the mass of the needle bar being such that the auxiliary elements and the needle bar require substantially equal driving forces, and the driving means for the auxiliary elements being so disposed with relation to those of the needle bar that the driving forces substantially oppose each other so that vibrational forces resulting from the driving of the needle bar are substantially neutralized.

3. A warp knitting machine comprising a sinker bar, balancing elements auxiliary thereto, means for actuating said sinker bar, and means for actuating said auxiliary elements in synchronism with but in the opposite sense to said sinker bar, the mass of the auxiliary elements in relation to the mass of the sinker bar being such that the auxiliary elements and the sinker bar require substantially equal driving forces, and the driving means for the auxiliary elements being so disposed with relation to those of the sinker bar that the driving forces substantially oppose each other so that vibrational forces resulting from the driving of the sinker bar are substantially neutralized.

4. A warp knitting machine comprising a presser bar, balancing elements auxiliary thereto, means for actuating said presser bar, and means for actuating said auxiliary elements in synchronism with but in the opposite sense to said presser bar, the mass of the auxiliary elements in relation to the mass of the presser bar being such that the auxiliary elements and the presser bar require substantially equal driving forces, and the driving means for the auxiliary elements

being so disposed with relation to those of the presser bar that the driving forces substantially oppose each other so that the vibrational forces resulting from the driving of the presser bar are substantially neutralized.

5. A warp knitting machine comprising a knitting element assembly, a plurality of operating and supporting members therefor, a plurality of balancing elements auxiliary to the knitting elements, driving means engaging said operating and supporting members to impart knitting movements to the knitting elements, and means for actuating said auxiliary elements in synchronism with but in the opposite sense to said knitting elements, the mass of the auxiliary elements in relation to the mass of the corresponding knitting elements being such that the auxiliary elements and the knitting elements require substantially equal driving forces, and the driving means for the auxiliary elements being so disposed with relation to those of the knitting elements that the driving forces substantially oppose each other so that vibrational forces resulting from the driving of the knitting elements are substantially neutralized.

6. In a warp knitting machine, knitting element operating and balancing mechanism according to claim 5, wherein the balancing members and driving means therefor are equal in number to and disposed close to their respective driving and supporting members for the knitting elements, so as to reduce to a minimum the couples resulting from the forces involved in driving the knitting elements and the balancing members.

7. A warp knitting machine comprising a knitting element assembly, a plurality of supporting members for said assembly, driving means for certain of said supporting members for actuating the knitting elements, balancing means auxiliary to the knitting elements, and means in connection with each of said driven supporting members for actuating said auxiliary elements in synchronism with but in the opposite sense to said knitting elements, the mass of the auxiliary elements in relation to the mass of the corresponding knitting elements being such that the auxiliary elements and the knitting elements require substantially equal driving forces, and the driving means for the auxiliary elements being so disposed with relation to those of the knitting elements that the driving forces substantially oppose each other so that the vibrational forces resulting from the driving of the knitting elements are substantially neutralized.

8. A warp knitting machine comprising knitting elements, balancing elements auxiliary thereto, means for actuating said knitting elements, and means for imparting to said auxiliary elements angular movements equal in magnitude and velocity but opposite in sense to those of said knitting elements, the mass of the auxiliary elements in relation to the mass of the corresponding knitting elements being such that the auxiliary elements and the knitting elements require substantially equal driving forces, and the driving means for the auxiliary elements being so disposed with relation to those of the knitting elements that the driving forces substantially oppose each other so that vibrational forces resulting from the driving of the knitting elements are substantially neutralized.

9. A warp knitting machine comprising a knitting element assembly, a plurality of operating and supporting members therefor, a plu-

- rality of balancing elements auxiliary to the knitting elements, driving means engaging said operating and supporting members to impart knitting movements to the knitting elements, and means for imparting to said auxiliary elements angular movements equal in magnitude and velocity but opposite in sense to those of said knitting elements, the mass of the auxiliary elements in relation to the mass of the corresponding knitting elements being such that the auxiliary elements and the knitting elements require substantially equal driving forces, and the driving means for the auxiliary elements being so disposed with relation to those of the knitting elements that the driving forces substantially oppose each other so that vibrational forces resulting from the driving of the knitting elements are substantially neutralized.
10. In a warp-knitting machine, a series of knitting elements, a bar carrying said elements, a plurality of operating and supporting members for said bar, driving means engaging said operating and supporting members to impart knitting movements to the knitting elements, a plurality of members respectively adjacent to said operating and supporting members and each comprising a plurality of weights adapted to balance the mass of the knitting elements and bar supported by the adjacent operating member, and driving means engaging said balancing members to impart thereto such movements of opposite sense to those of the knitting elements that the knitting elements and balancing means produce forces which substantially neutralize each other.
15. In a warp-knitting machine, a knitting element assembly, an operating cam adapted to impart knitting movements to said assembly, balancing means for said assembly, and an operating cam adapted to impart such movements of opposite sense to those of the knitting element assembly that the knitting element assembly and the balancing means produce forces which substantially neutralize each other, the respective operating cams being mounted close together on a common driven member so as to minimize the couple arising from the forces involved in their operation.
20. In a warp-knitting machine, needle-bar, sinker-bar and presser-bar assemblies, operating cams adapted to impart knitting movements to the respective assemblies, balancing means in connection with each assembly, operating cams adapted to impart to said balancing means such movements of opposite sense to those of their respective assemblies that each assembly and the balancing means produce forces which substantially neutralize each other, and a cam shaft, said cams being mounted on said cam shaft in pairs of which one cam is an assembly operating cam and the other a balancing means operating cam for that particular assembly.
25. In a knitting machine, a series of knitting elements, at least one cam having two operating surfaces, connecting means between said cam and knitting elements and having a cam follower engaging one cam surface to impart motion to the knitting elements in one direction and a second follower engaging the other cam surface to impart motion to the knitting elements in the other direction, balancing means for the series of knitting elements, and at least one cam for producing in the balancing means movements equal in velocity and magnitude but opposite in direction to those of the knitting elements, said cam having two operating surfaces for respective engagement with two cam followers similar to those of the knitting element operating mechanism.
30. In a warp-knitting machine, a plurality of knitting element assemblies, operating and supporting levers carrying the several assemblies, cams directly engaging said supporting levers so as to operate the assemblies, balance means in connection with each assembly, said balance means comprising weighted levers corresponding to the driven supporting levers of the respective assemblies, and cams directly engaging said weighted levers so as to impart such movements of opposite sense to those of their respective knitting element assemblies that each assembly and its balancing means produce forces which substantially neutralize each other.
35. A warp-knitting machine comprising needle, sinker, and presser bars, operating levers carrying said bars, a cam-shaft, a plurality of cams thereon adapted to engage said operating levers directly for operation of the needles, sinkers and presser carried by the bars, weighted levers adapted to balance the respective bars, and further cams on the cam-shaft adapted to engage the weighted levers directly and impart thereto such movements of opposite sense to those of the bars to be balanced that each bar and the balancing means therefor produce forces which substantially neutralize each other.
40. In a warp knitting machine, needle bar, sinker bar and presser bar assemblies, operating cams adapted to impart knitting movements to the respective assemblies, balancing means in connection with each assembly, operating cams adapted to impart to said balancing means angular movements equal in magnitude and velocity but opposite in sense to those of their respective assemblies so as to neutralize the forces produced by the movements of such assemblies, and a cam shaft, said cams being mounted on said cam shaft in pairs of which one cam is an assembly operating cam and the other a balancing means operating cam for that assembly.
45. A warp knitting machine comprising needle, sinker, and presser bars, operating levers carrying said bars, a cam shaft, a plurality of cams thereon adapted to engage said operating levers directly for operation of the needles, sinkers and presser carried by the bars, weighted levers adapted to balance the respective bars, and further cams on the cam shaft adapted to engage the weighted levers directly and impart thereto such movements of opposite sense to those of the bars to be balanced that each bar and the balancing means therefor produce forces which substantially neutralize each other.
